HANGER FOR SCREW CONVEYERS

Aubrey F. Hutchinson, Lamesa, Tex.

Application February 2, 1935, Serial No. 4,710

4 Claims. (Cl. 198—213)

This invention relates to hangers and more particularly to hangers for use with conveyers especially adapted for the conveying of cotton or the like.

5 An object of this invention is to provide a hanger for a conveyer such as a conveyer used in the movement of loose cotton which is so constructed that the hanger will not act as a means to clog the trough in which the cotton is moving 10 as is the case with hangers at present in use.

Another object of this invention is to provide a hanger of this type which is of simple construction and may be readily mounted on troughs at present in use for rotatably supporting the 15 conveyer shaft and the conveyer within the trough.

The above and various other objects and advantages of this invention will in part be described and in part be understood from the 20 following detailed description of the present preferred embodiment, the same being illustrated in the accompanying drawing wherein:—

Figure 1 is a detail side elevation partly broken away and in section of a hanger constructed according to an embodiment of this invention 25 showing the hanger in applied position on a trough, the trough and the conveyer within the trough being shown in dotted lines.

Figure 2 is a detail end elevation of the 30 hanger.

Referring to the drawing wherein like characters of reference designate corresponding parts throughout the views, the letter T designates generally a trough through which loose 35 cotton or the like is being conveyed and the letter C designates generally a conveyer of the screw type which is secured to a shaft S and which is rotatably supported within the trough T. This conveyer C preferably turns in the direction shown by the arrow in Figure 1.

In present constructions the shaft S is supported by a hanger which extends straight across the top of the trough T but in practice it has been found that this type of hanger is impractical due to the fact that one side of the hanger at the top of the trough has a tendency to cause a clogging of the cotton or other loose material. In order, therefore, to provide a suitable hanger 45 which will rotatably support the shaft S of the conveyer C within the trough T, I have provided a hanger comprising a vertically disposed arm 10 which is provided at the upper end thereof with a substantially right angularly disposed arm 11 secured as by bolts, screws or other fas-

tening devices 13 to one side of the trough T at the top thereof.

An arcuate arm 12 is integral with the dependent arm 10 and extends oppositely from the straight horizontally disposed arm 11 and is provided at its free end thereof with a lug 14 having suitable holes through which fastening devices 15 or the like may extend for securing the arm 12 to the top of the opposite side of the trough T.

The vertically disposed dependent arm 10 is provided at the lower end thereof with one-half portion of a bearing 16 and another half portion 17 of the bearing for the shaft S engages the integral bearing portion 16. Preferably the bearing 16 includes an inner shell 18 which may be formed of babbitt or the like. The removable bearing member 17 has a channel 19 in substantially the central portion thereof and a U-shaped bolt generally designated as 20 has the bight thereof engaging within the channel 19. The bolt 20 has one short leg 21 thereof extending along one side of the dependent arm 10 and this short leg extends through the inner end of the horizontal arm 11 and extends thereabove. A nut 22 engages the threaded upper end of the short leg 21. The other or longitudinal leg 23 of the U-bolt 20 extends on the opposite side of the dependent arm 10 and is adjustably secured as by a nut 24. The curved arm 12 extends above the top of the trough T for a suitable distance so that when the conveyer C is in operation and is rotating in the direction shown by the arrow in Figure 1, the cotton which is carried over the top of the conveyer C will not 30 contact with the supporting arm 12 as it moves longitudinally of the trough T and also transversely of the trough.

In the use of the hanger structure hereinbefore described, the laterally extending arms 11 and 12 are secured as by fastening means 13 and 15 to the upper ends of the trough T with the dependent arm 10 extending substantially downwardly through the center of the trough T in a position where the conveyer C will be rotatably supported adjacent the bottom of the trough T. Through the use of the U-bolt 20, the bearing including the two parts 16 and 17 may be adjusted so as to take up any wear caused by the shaft S or may be suitably replaced through the use of a replacement member similar to 17. The bearing 16 is lubricated by means of an oil channel 25 extending vertically through the dependent member 10.

What is claimed is:—

1. A hanger as set forth, comprising a pair of opposed arms, one of said arms being relatively straight and the other longitudinally curved, a dependent bearing supporting member integral with said arms and extending downwardly from the junction of said arms, and a bearing on the lower end of said member.
5
2. A hanger as set forth, comprising a straight arm, an upwardly curved arm opposed to said straight arm and integral therewith, said curved arm having the free end thereof terminating in a plane substantially coplanar with the lower side of said straight arm, a dependent bearing supporting member integral with each of said arms and extending downwardly from the junction of said arms, and a bearing at the lower end of said member.
10
3. A hanger as set forth, comprising a substantially straight arm, a longitudinally and upwardly curved arm integral with said straight arm and opposed thereto, said curved arm having the free end thereof terminating in a plane substantially coplanar with the lower surface of said straight arm, a dependent bearing supporting member integral with each of said arms and

extending downwardly from the junction thereof, a bearing member secured to the lower end of said supporting member, said bearing member including one portion integral with said supporting member and another portion detachable from said first portion, and means for securing said detachable portion to said first portion.
5

4. A hanger as set forth, comprising a substantially straight arm, a longitudinally and upwardly curved arm integral with said straight arm and opposed thereto, a dependent bearing supporting member integral with each of said arms and extending downwardly from the junction thereof, a bearing at the lower end of said supporting member, said bearing including one portion integral with the supporting member and another portion detachable from said first portion, a U-shaped bearing securing member engaging said detachable bearing portion and extending on opposite sides of said supporting member, said U-shaped bearing securing member having the free ends thereof extending through each of said arms, and means threadably securing the bearing securing member to said arms.
